UNITED STATES PATENT OFFICE.

HENRY DIEBEL, OF DETROIT, MICHIGAN, ASSIGNOR OF ONE-HALF TO W. H. WILCOX, OF DETROIT, MICHIGAN.

WIRE-FENCE FASTENER FOR CEMENT POSTS.

1,275,137.

Specification of Letters Patent. Patented Aug. 6, 1918.

Application filed May 15, 1918. Serial No. 234,655.

To all whom it may concern:

Be it known that I, HENRY DIEBEL, a citizen of the United States, residing at Detroit, in the county of Wayne, State of Michigan, 5 have invented a new and useful Wire-Fence Fastener for Cement Posts; and I do hereby declare the following to be a full, clear, and exact description of the invention, such as will enable others skilled in the art to which 10 it appertains to make and use the same.

The present invention relates to a wire fence fastening device for fence posts formed of plastic material such as concrete, and has for its object to provide a device of this 15 character which embodies novel features of construction whereby the wire fastening will be tightly gripped and held securely in position, although it can be readily detached when desired.

20 Further objects of the invention are to provide a device of this character which is comparatively simple and inexpensive in its construction, which will both reinforce the fence post and serve to ground any lightning 25 which may strike the fence, thereby avoiding much possible damage to livestock, and which will grip and hold the fencing against longitudinal movement, thereby relieving the anchor posts of all unnecessary strain.

30 With these and other objects in view, the invention consists in certain novel combinations and arrangements of the parts as will more fully appear as the description proceeds, the novel features thereof being pointed 35 out in the appended claims.

For a full understanding of the invention, reference is to be had to the following description and accompanying drawings, in which:—

40 Figure 1 is a front elevation of a fence post provided with a wire fence fastening strip constructed in accordance with the invention.

Fig. 2 is a side elevation of the same with 45 the post shown in section.

Fig. 3 is an enlarged detail view of a portion of the outer edge of the wire fence engaging strip, showing a fence wire as engaged within the lower wire receiving open-

50 ing.

Fig. 4 is an edge view of the same.

Fig. 5 is a horizontal sectional view through a portion of the outer edge of the strip, showing one of the wings in the posi-

tion normally assumed when not in engagement with a fence wire.

Fig. 6 is a similar view with the wing in the position assumed when in engagement with a fence wire.

Corresponding and like parts are referred to in the following description and indicated in all the views of the drawings by the same reference characters.

Referring to the drawings, which illustrate one embodiment of the invention, the 65 numeral 1 designates a concrete fence post which may be of any conventional construction, the lower end thereof being embedded in the ground 2. A sheet metal strip 3 extends longitudinally of the fence post, the 70 rear edge thereof being embedded in the fence post, while the outer edge thereof projects from the front of the post at substantially right angles thereto. The rear edge of the strip is shown as provided with a series of slits which extend downwardly at a sharp acute angle to the edge and form pointed tongues 4. These tongues are bent or twisted into irregular shapes so that when 75 embedded in the plastic body of the concrete post they serve to anchor the strip securely in position therein. The strip 3 thus strengthens and reinforces the post, and the lower end of the strip extends downwardly into the ground so that the strip will serve to 80 ground any lightning which may strike the fence. The possible injury or killing of live 85 stock by lightning is thus avoided.

The projecting outer edge portion of the strip 3 is provided with a series of openings 90 5 to receive fencing or fence wires such as is indicated at 6, the openings being slightly smaller than the wires and having sharp edges so that they will bite into and securely grip the fence wires. Each of the 95 openings 5 is intersected by a slit 7 which extends substantially longitudinally of the strip, said slits being shown as curved and as forming the inner edges of wings 8. There is one of the wings 8 for each of the 100 openings 5 and the wings have curved outer and upper edges, the curved edges thereof forming continuations of the sides of the curved slits 7, the upper ends of the slits opening through the edge of the strip into 105 V-shaped mouths 9 between adjacent wings 8 to admit of the fence wires being readily forced into position.

The upper ends of the wings 8 are normally deflected laterally to one side of the strip 3, as indicated by Fig. 1, although the deflection of the wings is considerably greater when fence wires are in engagement with the openings 5. The wires 6 have a diameter greater than that of the openings 5, and when a fence wire is forced into position the wing 8 is flexed laterally a considerable amount beyond normal in order that the two halves of the relatively small opening 5 may spread apart to provide a sufficiently large space to receive the fence wire, this being indicated by Fig. 6 and by the lower portions of Figs. 3 and 4. This is made possible by the fact that the slits 7 extend downwardly beyond the openings 5 so that the portions of the metal strip 3 containing the two halves of the openings can be sprung apart. The resiliency of the wings 8 will cause the sharp edges of the openings 5 to bite into and grip the fence wires, thereby holding the fence wires against longitudinal movement, and relieving the anchor posts of all unnecessary strain.

Having thus described the invention, what I claim as new and desire to secure by Letters Patent, is:—

1. A wire fence fastener for concrete posts, including a sheet metal strip adapted to have the inner edge thereof embedded in the body of the post with the outer edge thereof projecting from the post, said outer edge being provided with a series of wire receiving openings and being formed with substantially longitudinally extending slits intersecting the openings and extending beyond the same in both directions, one end of each of the slits opening outwardly through the edge of the strip and the said slits forming wings which are flexible to admit of fence wires being positioned within the openings.

2. A wire fence fastener for concrete posts, including a sheet metal strip adapted to have the inner edge thereof embedded in the body of the post with the outer edge thereof projecting from the post, said outer edge being provided with a series of wire receiving openings and being formed with longitudinally extending slits intersecting the openings, a wing being provided at the edge of the strip for each of the openings and said wings having curved outer and upper edges, the curved upper edge of each wing forming a continuation of the slit and the curved edges of adjacent wings providing flared mouths leading to the respective slits, the wings being flexible to permit of fence wires being positioned within the openings.

3. A wire fence fastener for concrete

posts, including a sheet metal strip adapted to have the inner edge thereof embedded in the body of the post with the outer edge thereof projecting from the post, said outer edge being provided with a series of wire receiving openings which have a diameter less than that of the fence wires to be engaged, and being also formed with longitudinally disposed slits which intersect the openings and extend in opposite directions beyond the same, one end of each of the slits being deflected outwardly and opening through the edge of the strip, the portions of the strip between the outer edge thereof and the slits forming wings which are adapted to be flexed laterally to position fence wires within the openings.

4. A wire fence fastener for concrete posts, including a sheet metal strip adapted to have the inner edge thereof embedded in the body of the post with the outer edge thereof projecting from the post, said outer edge being provided with a series of wire receiving openings which have a diameter less than that of the fence wires to be engaged, and being also formed with longitudinally disposed slits which intersect the openings and extend beyond the same in opposite directions, the edge of the strip being scalloped to provide wings having curved outer and upper edges, the upper edges of the wings being continuations of the respective slits and the curved outer edges of adjacent wings forming flared mouths leading to the slits, the wings being flexible to admit of the fence wires being positioned within the openings.

5. A wire fence fastener for concrete posts, including a sheet metal strip having the inner edge thereof slit to provide anchoring tongues adapted to be embedded in the post, while the outer edge thereof projects from the post and is formed with a series of wire receiving openings and longitudinally disposed slits intersecting the openings and extending in opposite directions beyond the same, the edge of the strip being scalloped to provide a series of wings having curved outer and upper edges, the curved upper edges forming continuations of the respective slits, while the curved outer edges of adjacent wings provide flared mouths leading to the slits, the wings being flexible to admit of the fence wires being inserted in position.

In testimony whereof I have signed my name to this specification in the presence of two subscribing witnesses.

HENRY DIEBEL.
